UNITED STATES PATENT OFFICE.

THADDEUS W. HEERMANS, OF EVANSTON, ILLINOIS.

DISH-WASHING MACHINE.

1,262,043.

Specification of Letters Patent. Patented Apr. 9, 1918.

Application filed May 18, 1917. Serial No. 168,952.

To all whom it may concern:

Be it known that I, THADDEUS W. HEERMANS, a citizen of the United States, and a resident of Evanston, in county of Cook 5 and State of Illinois, have invented certain new and useful Improvements in Dish-Washing Machines; and I do hereby declare that the following is a full, clear, and exact description thereof, reference being 10 had to the accompanying drawings, and to the characters of reference marked thereon, which form a part of this specification.

This invention relates to improvements in washing machines for washing dishes, silver- 15 ware, glasses and other articles, and the invention consists in the combination and arrangement of the parts shown in the drawings and described in the specification, and is pointed out in the appended claims.

20 The invention relates in part to a novel washing mechanism of the general character shown in my co-pending application for U. S. Patent, Serial No. 98245, filed May 18, 1916, wherein the container is divided into 25 a lower well or compartment for limiting the quantity of the wash water used and an upper washing compartment, with means for elevating the water from said well to the top of the washing compartment, whereby 30 the dishes are washed by water which flows always in one direction, or downwardly, the washing compartment being separated from the well by a series of wall members which are constructed and arranged to provide in- 35 direct passageways from the washing compartment to the lifting device, which are so formed as to provide settling, skimming and straining means to remove the particles from the wash water so that the water returning 40 to the water elevating means for re-use is clean.

The well is formed in a reduced bottom of the container so as to limit the amount of wash water handled and to correspond- 45 ingly limit the amount of fuel used to heat the water; it being apparent that inasmuch as the water is cleaned between its periods of use, a less volume of water may be used.

The invention relates also to a novel means 50 for supporting the container in such a relation to a kitchen sink or like fixture that the machine when not in use occupies normally unused space, so as to make the machine practicable in a small kitchen, the support

being so arranged that the machine is im- 55 mediately available when needed. In this respect the mounting or supporting frame for the container is adapted to be adjusted to any height of sink drain board and is so constructed as to require no plumbing or 60 fitting for connection to the sewer. The machine is also preferably provided with a burner whereby the water is kept hot and is not unduly chilled by coming in contact with the cold dishes. 65

The invention also relates to a novel power means for driving the operative elements of the washing machine, so constructed and arranged as to permit the container to be swung from a lower to a higher 70 position, either to bring the container into position for removing dishes from or placing the dishes in said container, or for raising the container so as to drain the water therefrom into the sink. 75

The invention has for its object to otherwise improve and simplify dish washing machines.

As shown in the drawings:—

Figure 1 is a side elevation of a dish 80 washing machine embodying my improvements, showing the container in two operative positions in dotted outline.

Fig. 2 is a partial front elevation and par- 85 tial section thereof somewhat enlarged.

Fig. 3 is a plan view of the machine, with parts broken away.

Fig. 4 is a detail section on line 4—4 of Fig. 1.

Fig. 5 is a detail of the water drain valve 90 fixture.

Fig. 6 is a detail of the locking latches.

As shown in the drawings, 10 designates a container, preferably made of sheet metal. It is provided with a removable cover 11, 95 and the bottom wall 12 thereof is formed with a depending reduced portion 13 which constitutes a well or compartment for the wash water. 14 designates a stand pipe that is arranged centrally within the container. 100 The lower end of said pipe is formed with a downwardly open bell mouth 15, arranged centrally within the well. The upper end of the stand pipe extends to the top of the container and said upper open end of the 105 stand pipe receives the lower end of a hollow bearing member 16, which is fixed to and depends from the removable cover and

is formed to provide orifices 17 of an umbrella spray nozzle in a manner generally similar to the construction shown in my aforesaid application. As herein shown said bearing member 16 is provided with an upwardly extending threaded neck portion 18 that extends through the sheet metal cover 11 and is locked thereto by means of upper and lower nuts 19, 20, respectively, threaded to said neck portion 18. 21 designates a helical impeller that is rotatively mounted within the bell mouth 15 of the stand pipe and which serves, when rotated at suitable speed, to lift the wash water upwardly through the stand pipe for discharge through the orifices 17 of the nozzle. The impeller is mounted on the lower end of a vertical, rotative shaft 22 which extends upwardly through the stand pipe and is rotatively mounted at its lower end in a bearing 23 carried by ribs 24 which are made integral with the bell mouth of the stand pipe. The shaft 22 extends at its upper end into a sleeve 26 that is rotatively mounted in an internal bearing of the member 16. Said shaft 22 is provided with a squared or other polygonal portion 29 which fits a like shaped portion of the opening of the sleeve, whereby the sleeve is non-rotatively locked to the shaft. Surrounding said sleeve and located in a yoke portion 27 of the member 16 is collar 28 which is locked to the sleeve by a set screw 30, said collar serving as a shoulder to hold the sleeve from rising in its bearing. Connected to or formed integral with said sleeve 26 is a driving wheel 32 which, as herein shown, is grooved for engagement with a cylindric driving belt, hereinafter described.

Surrounding the bell mouth 15 of the stand pipe and rising from the bottom of the well is an annular or ring like shell 35 which is formed at its upper edge to provide an inturned ledge 36. The internal diameter of said ledge is slightly greater than the external diameter of the base of the stand pipe, so that said stand pipe may be passed through the opening surrounded by the ledge, and thus removed from or inserted into place. Exterior to said annular shell 35 is an annular skirt 38 which is supported by webs 39 integral therewith and with the shell 35. Said skirt terminates some distance above the bottom of the well and its lower edge constitutes a skimming edge, for a purpose hereinafter described. The shell is surmounted by a dome shaped cover plate 40, which fits closely over and upon the upper edge of the shell and is formed with a central upwardly extending neck 41 that surrounds the stand pipe, whereby said plate may be removed upwardly over the stand pipe. Lugs 42 serve to center the dome shaped plate on said shell. Formed integral with the bell mouth of the stand pipe are

a series of webs 45 which carry an integral ring 46 that rests on the ledge 36, and said ring and a shoulder 48 on the stand pipe constitute a support for an annular screen 50 that bridges the annular open space between the stand pipe and the shell 35. The stand pipe is supported on the ledge 36 through the medium of the webs 45 and ring 46. A ring 51 is supported on the bottom of the well, and between said ring and integral therewith and with the shell 35 below the impeller 21, extend radial webs 52 that serve as means to break up the body of water in the well when the impeller is rotated and therefore prevent the body of water from being merely swirled by the impeller, with a result of losing the lifting effect thereof.

The dishes are contained in a basket-like holder 55 which is removably supported in the container, it being adapted to be supported on the bottom wall 12 and on said dome shaped plate 40. It may be made of any suitable form and is of a size to fit closely within the container. A silver rack 56 is supported on the bottom of the holder around the stand pipe and is adapted to be removed upwardly over the stand pipe.

The operation of the machine is generally like that of the machine illustrated in my aforesaid application. Water is placed in the container to about the level indicated in Fig. 2. The water may be heated before it is placed in the container or the water may be heated after being placed in the container and maintained hot by a suitable burner herein-after described. The impeller 21 is rotated rapidly through the medium of power applied to the pulley 32 and acts to force the water upwardly through the stand pipe, from whence it is discharged through the orifices of the nozzle and falls down among and through the dishes or other articles in the holder. The water after passing the dishes finds its way to the well through the indirect passages formed between the skirt 38 and shell 35 and through the screen 50. The solid, non-floating particles carried by the water settle by gravity to the lower part of the well exterior to the shell 35, while the solid, lighter particles, which float, are prevented from passing beneath the edge of the skirt 38, so that thereby said particles may be said to be skimmed from the water by said edge. Such particles as may, by reason of the agitation of the water pass said skimming edges are removed or separated from the water by the screen 50. The water returned to the impeller for re-use, therefore, is clean water and the dishes are not subjected to the application of an emulsion of the water and solids, such as would occur if the particles were not separated from the water between the periods of use thereof.

The water is preferably heated by a burner

located below the container so that it may be kept at a suitable high temperature, regardless of the chilling effect due to contact thereof with cold dishes and like articles.

5 The machine is of such size that it is adapted to be placed beneath an ordinary sink in a kitchen so that when not in use it occupies space that otherwise is of little value. In order that free access may be had 10 to the machine for placing the dishes and other articles thereinto and for removing them and also for emptying water from the machine, said machine is movably supported on a frame that rests preferably on the floor, beneath the sink, and embraces a swinging hanger-like arrangement which permits the machine to be shifted to the dotted line positions shown in Fig. 1; the intermediate position being one at which the machine may be 15 charged with and emptied of articles to be washed, and the upper position being one at which the water may be drained from the machine into the sink S. The frame for this purpose is made as follows:—58, 58 designate side frame members which are connected at their upper ends by a cross bar 59 and at their lower ends by tie rods 60 which extend through spacing tubes 61 and coöperate with nuts 62 threaded to the ends of 20 the rods to space and rigidly connect the side frame members. They are also connected in rear of the machine by means of a motor supporting board 63 that extends between and is supported on and attached to 25 brackets 64 integral with the said frame members. Arranged just inside each side frame are upper and lower pairs of L-shaped levers 66, 67 respectively; the levers 66 being inside of the levers 67. The shorter arms of 30 the upper lever 66 are hinged at their ends to studs 68 on the side frames near the upper ends of the latter and the ends of the longer arms of said levers 66 are hinged, by means of studs 69, to ears 70 of hanger brackets 35 71 that are secured to the container near the bottom of the latter. The ends of the shorter arms of the lower levers 67 are hinged by studs 72 to downwardly extending arms 73 fixed to or made integral with the brackets 40 71. The said arms 73 are offset outwardly from the brackets 71 for a purpose herein-after to be explained and said arms are strengthened by ribs, as best shown in Figs. 45 1 and 2. The longer ends of said lower levers 67 are hinged by studs 75 to enlarged portions 50 76 of the side frame members near the plane of the top of the container 10. The said longer arms of the lower levers are provided with rigid, rearwardly directed arms 60 80 which are connected by links 81, 81', through the medium of hinge studs 81', to the shorter arms of the upper levers adjacent to their junctions with the longer arms of 55 the latter.

65 On the pivot studs 75, by which the longer

arms of the lower levers 67 are connected to the frame, are mounted crank plates 82 which are connected by bolts 83, that extend through said plates and bosses thereof, to the arms 80, as best shown in Fig. 4, said 70 bolts being spaced a substantial distance radially from the studs 75. The said crank plates, herein shown as made triangular, are provided with studs 84 which are disposed on said crank plates on the sides of the axes 75 of the hinge studs remote from the bolts 83. Between the studs 84 and fixed parts of the frame at the lower side thereof, as herein shown one of the tie rods 60, are stretched counterbalancing springs 85, consisting of 80 spiral tensile springs. The said bolts 83, located as shown a substantial distance from the hinge studs 75 in connection with bosses 83', constitutes a rugged connection between the crank plates and the arms 80 of said 85 lower levers 67 and ample leverage for a purpose hereinafter referred to. The crank studs 84 are furthermore so related to the hinge studs 75 and to the bolts 83 that when the container is in its normal lowermost 90 position said studs 84 are located slightly forwardly of a line passing through the rear tie rod 60 and the hinge studs 75, so that the tensile energy of the springs acts on the upper ends of said levers 67 in a manner 95 tending to hold the container in its downward and rearmost position.

The said container is locked in its rear-most position by means of locking latches 88 that are pivoted in any suitable manner 100 at the rear end of the machine to ears or lugs 89 on the motor supporting table 63. As herein shown said latches comprise the arms of a bail-like member, the central portion 90 of which lies over the motor table 105 63. The said central portion of the latch arms is raised upwardly above the level of the pivots thereof, and is borne upon by a spring 91 attached to the motor supporting board or table 63. The forward ends of said 110 latches are formed to provide upwardly opening locking notches 92 adapted to engage studs 93 fastened to and extending laterally from the sides of the container just below the cover thereof. Said latches are 115 continued forward beyond said notches to provide operating extensions 94 by which they may be operated to release them from said studs; and the spring 91 acts on said connecting member of the latches in a way 120 to hold the latches upwardly against said studs 93.

In the operation of swinging the machine from its normal lowermost position to either of the positions shown in dotted lines Fig. 125 1, the upper and lower levers 66, 67 swing respectively, on the hinge studs 68 and 75, and the connection of the links 81 between the short right angle arms 80 of the lower levers and the shorter arms of the upper 130

levers provide a parallel lever motion which maintains the container of the machine always in an upright position.

The machine is locked in the intermediate dotted line position, or that beyond the drain board of the sink, by engagement of the notches 92 of the latches 88, with studs 99 which may constitute extensions of the hinge studs 81' by which the links 81 are connected to the short arms of the upper pair of levers 66. When the machine is raised to the highest position, shown in dotted line Fig. 1, the crank bolt 83 of the crank plate 82 swings downwardly just short of the center of the hinge stud 75, so that the said springs 85 act against the crank plate and its driving connection to the rigid arms 80 of the lower pair of levers to hold the machine in its upper position. When the machine occupies this position, the longer arms of the upper pairs of levers 67 are seated in the offset portions of the arms of the brackets 71, against the bottoms of said offset portions, so that the said levers act against the bottoms of said offset portions as stops to limit the action of the springs 85.

The water may be heated and kept hot in the container through the medium of burners 105 which are connected to a gas supply pipe 106, said burners being located immediately beneath the reduced bottom or the well of the container. The burners are supported in any suitable manner on the frame and remain stationary when the machine is swung forwardly and upwardly.

Preferably means are provided for adjusting the machine to different heights of sinks. This is shown as effected in the present instance by providing screw threaded legs 107 which are threaded through bosses 108 in the side members of the frame and said legs may be locked thereto by locking nuts 109. The rear legs may be provided with rollers 110 in order to facilitate movement of the machine from place to place on the floor.

Preferably the machine is motor driven and a driving arrangement is provided which permits the machine to be swung away from the driving mechanism and to be swung backwardly into connection therewith by means which automatically connects the driving mechanism to the moving parts of the machine. The construction shown by which this result is effected is made as follows:—

115 designates an electric motor which is mounted on the motor table 63 and is supported thereon by upright angle supporting members 116 which engage with and are attached to the usual feet of a horizontal motor to hold the motor in an operative upright position. A pulley 117 fixed to the upper end of the armature shaft lies in the

plane of the operating pulley 32 of the impeller shaft of the washing machine. 119 designates a belt which is trained about the pulley 117, and is also trained about idler pulleys fixed to the frame in such a way that the pulley 32 is engaged in a bight of the belt instead of being encircled thereby. To this end the belt is trained about two idler pulleys 120, one at each side of the driving pulley 32, and said pulleys 120 are 75 rotatively mounted on axes carried by the outer ends of arms 122 that are hinged at 123 to the top cross member 61 before referred to. The said arms 122 are provided at their ends, and at their proximate sides, 80 with upwardly extending lugs 125, and the cross frame 61 is provided with forwardly extending arms 126 which terminate in downwardly turned lugs 127. 128 designates a curved guide rod which is fixed in 85 any suitable manner at its ends to the lugs 127 and is curved around the driving pulley 32 and is extended freely through said upturned lugs 125 of the arms 122. Surrounding said rod between said arms 122 is a 90 spiral expansively acting spring 130 which has a normal tendency to force the arms away from each other.

When the washing machine is in its lowermost normal position for operation, the 95 pulley engages the bight of the belt between the idler pulleys 120, in the manner shown in Fig. 3, so as to effect a driving connection of the belt with said pulley, and the spring 130 at this time serves to hold the 100 belt tightly against the pulley. When the pulley 32 is moved away from the belt, however, in drawing the machine forwardly and upwardly, the spring 130 serves to force the arms 122 away from each other and to take 105 up the slack due to the bight in the belt, so that the belt will run tight about the motor and idler pulleys without a tendency to jump off said pulleys. Stops 134, 134, formed on the ends of arms 135 which 110 spring rearwardly from the lugs 127 act on the lugs 125 to maintain the spring 130 in central or symmetrical position with respect to the axis of the arms 122, and to limit the movement of the arms 122 when the pulley 115 32 is in contact with the belt 119.

The drain valve for the container is shown in detail in Fig. 5, and in assembled relation in Figs. 1 and 2. It is made as follows:

137, 137 designate pipes that are connected in any suitable manner with the well through the bottom wall thereof and are formed centrally of the well to provide a valve chamber 138 to receive a rotating 125 plug 139 that is provided with oppositely located ports which when the plug is rotated 90 degrees from the position shown in Fig. 5 are brought into register with the passage 137. As shown in Fig. 5, the pipes 137 com- 130

municate with the well through hollow screws 140 that fasten the valve casting, including the chamber 138, and the pipes 137, to the bottom of the well. The plug 5 communicates with an outlet orifice 141 formed in a radial handle member 142 whereby the drain water is directed laterally from the axis of the plug. In adapting the machine to different sinks the lateral distance from this axis of the plug to the sink is likely 10 to vary, and to provide for this contingency, I provide the combined nozzles and handle with an extension trough 143, which may be made of sheet metal and slidably fitted thereto. Said drain trough is formed with 15 stops 144 at its ends to limit its sliding movement with respect to the handle and nozzle and is also provided with finger pieces 145 by which it may be conveniently shifted into proper adjustment. The trough 20 is made of such length that the drain will be adapted to any sink.

I claim as my invention:

1. A washing machine comprising a container and its washing mechanism, a frame therefor, and a system of swinging, parallel moving levers pivoted to said frame and to the container by means which support the container normally below the level of the pivots which connect said levers to the frame, said levers adapted to be swung outwardly and upwardly away from the frame, and having means to hold the container upright in said last named position.

2. A washing machine comprising a container and its washing mechanism, a frame therefor, and a system of swinging, parallel moving levers pivoted to said frame and to the container by means which support the container normally below the level of the pivots which connect said levers to said frame, said levers adapted to be swung outwardly and upwardly away from the frame, and having means to hold the container upright in said last mentioned position, with means to hold the container in its outwardly swung or extended position.

3. A washing machine for the purpose set forth comprising a container and its washing mechanism, a support therefor comprising a frame, upper and lower pairs of levers, the upper pair of levers being pivoted at their upper ends to the frame and at their lower ends to the container and the lower 55 pair of levers being pivoted at their lower ends to the container and at their upper ends to the frame, means connecting said levers to cause them, when swung on their pivots, to maintain the container in upright 60 position when the container is drawn outwardly from and above the frame, and counterbalancing means for the moving parts.

4. A washing machine for the purpose set forth comprising a container and its wash-

ing mechanism, a support therefor comprising a frame, upper and lower pairs of levers, the upper pair of levers being pivoted at their upper ends to the frame and at their lower ends to the container and the lower 70 pair of levers being pivoted at their lower ends to the container and at their upper ends to the frame, means connecting said levers to cause them, when swung on their pivots, to maintain the container in upright 75 position when the container is drawn outwardly from and above the frame, latch means to lock the frame in its normal lower and outwardly swung positions, and counterbalancing means for the moving parts. 80

5. A washing machine for the purpose set forth comprising a container and its washing mechanism, a support therefor comprising a frame, upper and lower pairs of levers, the upper pair of levers being pivoted at their 85 upper ends to the frame and at their lower ends to the container and the lower pair of levers being pivoted at their lower ends to the container and at their upper ends to the frame, links connecting said levers to provide a parallel lever movement to hold the container in upright position when the container is swung outwardly and upwardly from said frame, and counterbalancing 90 springs connected to said frame and to said system of levers.

6. A washing machine comprising a container and its washing mechanism, a frame therefor comprising fixed side members, upper and lower pairs of swinging curved 100 levers, with the upper ends of the upper pair of levers pivoted to the frame and with the lower ends thereof pivoted to the container, and with the upper ends of the lower pair of levers pivoted to the frame and the 105 lower ends thereof to the container, the upper ends of the lower levers being provided with rigid, angularly disposed arms, links connecting said arms with the upper ends of the upper levers, and counterbalancing 110 means connected to the frame and the system of levers.

7. A washing machine comprising a container and its washing mechanism, a support for the container embracing a fixed frame, upper and lower pairs of swinging levers, with the upper ends of the pairs of levers pivoted to the frame respectively at vertically spaced points and with the lower 115 ends of the pairs of levers pivoted to the 120 container respectively at vertically spaced points, links connecting said upper and lower pair of levers to constitute a system of parallel moving levers constructed to maintain the container upright when swung 125 outwardly and upwardly, and counterbalancing means between the frame and said system of levers.

8. A washing machine comprising a container and its washing mechanism, a frame 130

in which the container is mounted embracing upper and lower pairs of swinging levers, with the upper ends of the pairs of levers pivoted to the frame respectively at 5 vertically spaced points and with the lower ends of the pairs of levers pivoted to the container respectively at vertically spaced points, means connecting said levers to constitute a system of parallel moving levers 10 arranged to maintain the container upright when swung outwardly and upwardly, and latching means to lock the container in its normal lowermost position, with means coöperating with the latching means for 15 locking the container when swung outwardly away from the frame.

9. A washing machine adapted for use under a kitchen sink, comprising a container and its washing mechanism, and a support 20 therefor comprising a fixed frame and swinging members hinged to the frame and the container and constructed with means to carry the container, always in an upright position, to a point above the sink and 25 frame.

10. A washing machine comprising a fixed frame, a container and its washing mechanism, a swinging hanger hinged to the frame and to the container and constructed with 30 means to carry the container, always in an upright position, away from the frame, a motor mounted on the frame and provided with a driving pulley, an operating pulley connected to the washing mechanism, a belt 35 trained about the motor pulley and provided with a bight to engage partially around the operating pulley, and means to take up the slack in the belt, due to said bight, when the operating pulley is moved away from the 40 belt.

11. A washing machine comprising a fixed frame, a container and its washing mechanism, a swinging hanger hinged to the frame and to the container and constructed with means to carry the container, always in an upright position, away from the frame, a motor mounted on the frame and provided with a driving pulley, an operating pulley connected to the washing 45 mechanism, swinging arms at the sides of the operating pulley having guide pulleys, a belt trained about said motor pulley and about the guide pulleys to form a bight to partially engage around the operating pulley, and means tending to force said arms 50 55

away from each other to straighten said bight.

12. A washing machine comprising a fixed frame, a container and its washing mechanism, a swinging hanger hinged to the frame and to the container and constructed with means to carry the container, always in an upright position, away from the frame, a motor mounted on the frame and provided with a driving pulley, an operating pulley connected to the washing mechanism, swinging arms at the sides of the operating pulley having guide pulleys, a belt trained about said motor pulley and about the guide pulleys to form a bight to partially engage 60 around the operating pulley, a fixed rod extended through lugs on said levers and a compression spring surrounding the rod and tending to separate said arms. 70

13. In a washing machine, a fixed frame, a movable support in the frame for said machine, a washer mechanism driving pulley carried by and movable with the machine, a motor mounted on the frame, and having a driving pulley, a driving belt trained about 80 said driving pulley and engaging the operating pulley, and means to automatically disengage said belt from and engage it with the said operating pulley when said machine and its operating pulley are moved, respectively, from and toward said fixed frame. 85

14. In a washing machine a fixed frame, a movable support in the frame for said machine, a washer mechanism operating pulley carried by and movable with the machine, a 90 motor mounted on the frame and having a driving pulley, a driving belt trained about said driving pulley, guide pulleys at the sides of the operating pulley movable toward and away from each other about which 95 said belt is trained and arranged to form between them in the belt a bight to engage the operating pulley and a spring acting against the tension of said belt tending to force said pulleys apart. 100

In witness whereof I claim the foregoing as my invention, I hereunto append my signature in the presence of two witnesses at Chicago, Illinois, this 14th day of May, 1917.

THADDEUS W. HEERMANS.
